FURNITURE LEG CONNECTION FOR CHANNEL FRAMES

Filed April 23, 1947

UNITED STATES PATENT OFFICE

2,516,933

FURNITURE LEG CONNECTION FOR
CHANNEL FRAMES

Donald A. Wallace, New York, N. Y.

Application April 23, 1947, Serial No. 743,325

3 Claims. (Cl. 311—110)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to a furniture-leg connection, and more particularly to means for attaching a leg to a channel-iron furniture frame. It is well known in the furniture art to attach a furniture leg to a furniture body by means of a corner bolt extending inwardly of the frame at an angle of about 45° and passing through the leg. Such a construction has the advantages of being simple and secure, and capable of quick and easy adjustment. However, it has been found that corner bolts are difficult to apply to furniture frames of channel-iron construction, as it is difficult to secure a firm connection between frame and corner bolt which is capable of withstanding the compressive and shearing forces acting on the furniture after connection of the leg. This difficulty has heretofore imposed a limitation on the designing of furniture of channel-iron construction, and has thus compelled the art to forego to a large extent the strength, rigidity and agreeable appearance of a channel-iron frame.

It is thus one of the primary objects of the present invention to provide novel means for associating a corner bolt connection plate with a channel-iron furniture frame.

Another object of the invention is a corner bolt connection plate associated with a channel-iron furniture frame in such a manner that the frame is strengthened by such association.

A further object of this invention is a simple and inexpensive support for a furniture corner bolt, which can be easily and cheaply made of conventional construction material.

Still another object of this invention is a device for attaching a furniture leg to a channel frame in such a manner that the furniture leg is in area contact with the device which forms a bearing surface therefor, but out of contact with the web of the channel frame and in not more than line contact with the flanges of the frame.

Other objects and advantages of my invention will readily appear from the following description thereof in connection with the appended drawings wherein:

Fig. 1 is a perspective view of a table having a channel-iron apron and legs attached hereto by novel means in accordance with my invention;

Fig. 2 is a perspective view, on an enlarged scale, of an embodiment of my furniture-leg at-

2

tachment means just prior to its assembly with the furniture frame;

Fig. 3 is a sectional view, on an enlarged scale, taken along lines 3—3 of Fig. 1;

Fig. 4 is a sectional view, on an enlarged scale, taken along lines 4—4 of Fig. 1; and

Fig. 5 is a sectional view corresponding to the view presented in Fig. 3, but showing a modified form of my furniture-leg attachment means.

My invention consists briefly of a plate having an angled web and perpendicular flanges interfitting with the channel of a channel-iron furniture frame, and associated therewith one or more corner bolts extending inwardly for the attachment of a furniture leg.

More particularly, reference numeral 10 denotes a channel-iron frame of an item of furniture, which in the appended drawings is represented in the form of a table. The term "channel iron" is meant to denote any structural material (not necessarily iron), having a web 11 and a pair of flanges 12, 12' extending substantially perpendicularly therefrom at its edges. A construction made of such channel iron material possesses great strength and a pleasing appearance, particularly when the flanges of the frame are directed inwardly and are thus not visible when the completed article is viewed from an ordinary angle of observation.

The leg connection to such a channel-iron frame in accordance with my invention comprises a short channel-iron plate interfitting with the channel-iron frame 10; namely, web 13 bent at the same angle as a corner of frame 10 (usually a right angle), and flanges 14, 14' extending perpendicularly from the web in an outward direction. The width of the attachment plate equals the clearance between flanges 12, 12' of frame 10.

In one embodiment of my invention, illustrated in Figs. 2 to 4 of the drawings, bolts 15, 15' are welded to, or otherwise associated with, the angle plate at the angle enclosed by web 13; a preferred way to accomplish this is to emboss the web 13 outwardly at 16, 16' to provide seats for the bolt heads 17, 17' in the space between flanges 14, 14'. The shanks of bolts 15, 15' thus extend in a direction opposite the direction of flanges 14, 14' and at an angle precisely or approximately bisecting the angle enclosed by web 13.

To assemble frame 10, attachment plate 13, 14, 14' and a furniture leg 18, the attachment plate is inserted in the frame and connected thereto, e. g., by spot-welding the flanges 14, 14' to flanges 12, 12'. In this manner, web 13 and

bolt heads 17, 17' connected thereto are spaced from frame 10 by the flanges 14, 14', as is best seen in Figs. 3 and 4. Leg 18, provided with spaced perforations 19, 19', 20, 20', is next put in place by inserting bolts 15, 15' in such perforations. Leg 18 may be either solid, or, preferably because of the lighter weight, hollow. In the case of a hollow leg, I prefer to align spacers 21, 21' with perforations 19, 19', 20, 20' inwardly of the leg. Finally, nuts 22, 22' are placed over the threaded free ends of bolts 15, 15' and tightened. Where the inner edge of leg 18 slants, a perforated wedge 23 is advantageously inserted between the leg and the nuts. Spacers 21, 21' prevent deformation of the hollow leg, which otherwise might result from tightening nuts 22, 22'; I prefer to make the spacers of resilient material, such as spring steel. A secure attachment of the leg to the frame is thus provided through the substantial bracing contact between angle plate and leg, and the frame is protected against deformation at its corners by reason of the bracing action of the attachment plate.

In a modified form of my invention, illustrated in Fig. 5, an interiorly threaded sleeve, such as nut 24 is welded or otherwise secured to embossed seat 16" on the outside of web 13" of a flanged attachment plate. In this modified form, leg 18" (and spacer 21" and wedge 23") are aligned with web 13" to permit the insertion of separate bolt 25 therethrough and through nut 24 whose bore defines a passageway with an axis precisely or approximately bisecting the angle formed by web 13". The length of bolt 25 is such that its threaded end 26 will engage and pass through the inner bore of nut 24 but will not touch frame 19".

I have thus described two embodiments of my invention, as applied to a table, and in connection with a hollow tapering furniture leg, as disclosed and claimed in my co-pending design patent application Serial No. D. 132,187, "Furniture Leg," filed August 1, 1946, now Design Patent No. D. 155,369, dated September 27, 1949. However, as has been pointed out, my invention is equally applicable to other types of furniture and legs with equal advantage. Modifications and adaptations of my invention by minor changes in dimensions and proportions, or by varying the number of bolts, etc., are readily within the reach of the expert, and thus fall within the scope of my invention. I therefore desire to be limited only by the appended claims.

I claim:

1. A device for attaching a furniture leg to a channel frame, comprising an angle plate, an upper and a lower flange of substantial width extending perpendicularly outwardly from said angle plate, and a bolt extending inwardly from said angle plate into the angular space enclosed by said angle plate; said angle plate maintaining said furniture leg in substantial bracing contact,

but in not more than line contact with said channel frame, when said furniture leg, angle plate and channel frame are in assembled relation.

2. In combination with a furniture frame comprising a web forming a corner and a pair of flanges perpendicular to said web: an angle plate paralleling said corner and interfitting with and bracing said frame, said plate having outwardly extending perpendicular flanges abutting against the web of said frame and interfitting with and at least as wide as the inner walls of the flanges of said frame and spacing said plate from said web, and a furniture leg attachment bolt extending from said plate in a direction opposite that of said last-named flanges for securing a furniture leg to said frame; the inner surface of said angle plate forming a bearing surface maintaining said furniture leg in spaced relation from the web of said frame for a distance at least equal to the width of the flange walls of said frame.

3. In combination: a furniture frame comprising a web forming a corner and a pair of flanges perpendicular to said web; a detachable furniture leg; an angle plate paralleling said corner and interfitting with and bracing said frame, said plate having outwardly extending perpendicular flanges abutting against the web of said frame and interfitting with and at least as wide as the inner walls of the flanges of said frame and spacing said plate from said web, and an interiorly threaded sleeve seated on the outside of and integral with said plate at the angle formed by said plate; and a furniture leg attachment bolt having a threaded tip removably received in said sleeve, said bolt extending from said plate in a direction opposite that of said last-named flanges for securing the furniture leg to said frame; the inner surface of said angle plate forming a bearing surface maintaining said furniture leg in spaced relation from the web of said frame for a distance at least equal to the width of the flange walls of said frame.

DONALD A. WALLANCE.
